UNITED STATES PATENT OFFICE.

HAROLD D. PENNEY, OF PELHAM, NEW YORK, ASSIGNOR TO ROBERT L. McELROY, OF NEW YORK, N. Y.

DIAPHRAGM-MOUNTING.

1,299,604.

Specification of Letters Patent.

Patented Apr. 8, 1919.

Application filed June 28, 1916. Serial No. 106,304.

To all whom it may concern:

Be it known that I, HAROLD D. PENNEY, a citizen of the United States, residing in Pelham, in the county of Westchester and State 5 of New York, have invented certain new and useful Improvements in Diaphragm-Mountings, of which the following is a specification.

My present invention relates to an improvement in diaphragm mountings and has 10 for its object the provision of a novel form of attachment of the mica diaphragm to the sound-box, housing, or in the present instance, a frame, which may be attached to 15 the sound-box in the customary manner, and is similar in some respects to and has for its accomplishment the same purpose as set forth in my copending application, Serial No. 106,303, filed June 28, 1916, of even date 20 herewith, wherein there is also shown the use of a resilient or yielding means between the diaphragm-disk and its mounting frame or anchorage, but the same differs greatly in construction from the device herein shown.

One of the objects of my invention is to 25 so mount the usual diaphragm as to not only cause it to become integral with its mount and to hold it in operative position therewith, but also to provide that the means 30 for mounting the said diaphragm will not only be economical in manufacture, but will tend to increase the tone volume of the diaphragm by permitting a greater amplitude or movement of the diaphragm, thereby 35 displacing a greater volume of air.

To the accomplishment of the above stated 40 object, and others of a similar nature, my invention consists in the construction, combination and arrangement of parts set forth in 45 and falling within the claims forming part hereof. And it should be understood that I do not confine myself to all the details of construction, as there may be modification thereof and variation therein without departing from the spirit of my invention or 50 exceeding the scope of the claims.

In the accompanying drawings, Figure 1 is a front elevation of my device.

Fig. 2 is a sectional view thereof taken on 55 the line 1—1, of Fig. 1.

Fig. 3 is an enlarged fragmental section thereof, showing the components, and

Fig. 4 shows one method of mounting the diaphragm in its frame.

Heretofore in diaphragm mountings it has 55 been the custom to provide either in a ring frame which may be screwed into the housing of a diaphragm, or in the housing itself, a suitable recess into which a sheet of resilient compound, usually a ring of rubber, is 60 placed and the mica diaphragm is thereafter placed in position and another insulator rubber ring is placed thereon and then a metallic retaining ring is screwed into position clamping the diaphragm between two 65 rubber seats, thereby preventing contact with the metallic parts thereof and forming a semi-resilient seat, under compression, whereby to prevent the so called "singing" 70 of the diaphragm when in use.

In my invention, as indicated in Figs. 2, 3 and 4, I provide an annular holder member 1 which is provided with threads 2, in the customary manner, whereby the said diaphragm and holder may be screwed in and 75 out of the sound-box for replacement and repairs, and instead of clamping the diaphragm 5 rigidly between two yielding members and a non-yielding member, I provide a simple recess 3 in the annular frame 80 or holder member 1, and with the diaphragm 5 being held in operative position in said recess 3, I cause to be introduced in said recess, and in and around said diaphragm, a filling of Para rubber 4, which rubber not 85 only fills all of the recess 3, but also surrounds the edges of the diaphragm 5. The assembly, as above described, is then placed in suitable molds, such as 6 and 7, and the annular frame and diaphragm are thereupon 90 vulcanized together, without tension or compression of the diaphragm.

It is obvious that the molds preferably should be so arranged as to not only mold the resilient filler 4 to the desired conformation, 95 but so that it will also locate the diaphragm to the desired depth in the recess 3, and also hold it concentric to the annular member 1, at the same time holding the annular member 1 in its relative position thereto. Modifications of this mold may be made, but still the main requirements, as applied to commercial manufacturing of such diaphragm, would be about as above set forth.

While I use Para rubber owing to its resiliency and toughness, other suitable materials might be used in substitution therefor without departing from the spirit of my invention.

tion. It is obvious, owing to the construction set forth, that the diaphragm is mounted in its holder frame in such a manner that while it is held against "singing vibration" it is also firmly connected with the said annular member by a non-vibrant yielding connection, and that therefore, the diaphragm is permitted a greater scope of movement, the said diaphragm being substantially permitted to float in its frame connections, and that in use, the amplitude of the diaphragm will be greater, thereby effecting a greater volume of air, and hence, increasing the amount of sound that may be obtained therefrom.

I claim:

1. A diaphragm mounting comprising an annular-holder or ring-frame having an annular recess in the inner peripheral wall, a diaphragm disk, and an annular supporting ring of soft, elastic, resilient material, located in said recess and secured thereto and inclosing and secured to the peripheral edge of the diaphragm disk whereby to provide a floating annular support to hold the diaphragm disk in operative position.
2. A diaphragm mounting comprising an annular-holder or ring-frame having a two-walled annular recess in the inner peripheral wall face, a diaphragm disk, and an inside supporting ring of soft, elastic, resilient ma-

terial, located in said recess and secured thereto and inclosing and secured to the peripheral edge of the diaphragm disk to inclose the entire peripheral edge thereof and hold the diaphragm disk resiliently and in operative position at a predetermined distance from the walls of the annular recess of the annular-holder or ring-frame.

3. A diaphragm mounting comprising an annular-holder or frame-ring having a two-walled annular recess in the inner peripheral wall face, said recess being open toward the face and also toward the center of the annular-holder or ring-frame, the wall from the side face of the recess being substantially at a right angle to the wall leading from the peripheral wall face, a diaphragm disk, and an annular supporting ring of soft, elastic, resilient material, located in said annular recess and secured thereto and inclosing and secured to the peripheral edge of the diaphragm disk, and forming a floating annular support to hold the diaphragm disk by its periphery, without use of other means, a predetermined distance from the walls of said annular recess and in operative position.

HAROLD D. PENNEY.
